MATCH RECEPTACLE.

APPLICATION FILED MAY 2, 1907.

Fig. 1.

UNITED STATES PATENT OFFICE.

NILS O. BULL, OF KONGSVINGER, NORWAY, AND FREDRIK BLOM-OHLSEN, OF NEW YORK, N.Y.

MATCH-RECEPTACLE.

No. 888,462.

Specification of Letters Patent.

Patented May 26, 1908.

Application filed May 2, 1907. Serial No. 371,381.

To all whom it may concern:

Be it known that we, NILS OTTO BULL and FREDRIK BLOM-OHLSEN, subjects of the King of Norway, residing, respectively, at 5 Kongsvinger, Norway, and borough of Brooklyn, city and State of New York, have invented certain new and useful Improvements in Match-Receptacles, of which the following is a full, clear, and exact description.

10 Our invention relates to a construction of match safe or receptacle for containing safety matches of that type which light only on a prepared surface of the box.

By the present invention a magazine is 15 provided to receive a supply of these match boxes, and to permit the matches thereof to be obtained only one by one, and to be ignited on the prepared surface above mentioned.

20 The only form of match which is regarded as really safe is that kind, above mentioned, which will not light on ordinary surfaces, but has to be scratched on a prepared surface, which is usually furnished on the side of the 25 box in which the matches are packaged. These matches are almost universally put up in small oblong wooden boxes about two inches long or thereabouts, and are widely used in connection with special holding devices for conveniently supporting the box. In view of the fact that this style of match and its boxes have become in a sense standardized, it is possible to provide a magazine or storage receptacle for the boxes, and 30 35 which serves special purposes, as in the present invention.

The aim of our present invention is to receive and store a number of these boxes of matches so as to have an adequate supply, 40 but have them so contained in their receptacle that all of the matches of each box must be individually used up one by one before another box may be obtained from the magazine. In this way it is possible to have 45 a match safe hung in any public place, and filled with boxes of matches, without the liability of unscrupulous persons helping themselves to an undue supply.

The apparatus is further designed to be 50 cheaply manufactured from sheet metal, without the use of any expensive or specially manipulated locks or devices, but merely certain parts which are self-locking by the action of the matches themselves. At the 55 same time the match safe always presents a box in such a way that a surface is available

to scratch the matches on, and this surface is renewed every time a new box of matches is used.

With these purposes and objects in view 60 the invention consists in the features of construction and combination hereinafter set forth and claimed.

In the drawings: Figure 1 is a side view partly in section of a match safe or receptacle embodying the principles of our invention; Fig. 2 is a side view of the same partly in section; Fig. 3 is a view partly in section, looking downward on the top of the receptacle. 70

Referring to the drawings in which like parts are designated by the same reference sign, 1 indicates a plate or base which constitutes the main support for the receptacle. This plate is conveniently made with a hole 75 2, near its upper end by which it may be hung on the wall or convenient place.

3 indicates a similar hole at the bottom of the plate 1, for an additional fastening means. These openings are shown of key-hole form 80 so as to be firmly engaged over the nails or fastening devices on which they are placed.

The main body of the receptacle is indicated at 4, and comprises a sheet metal strip or body bent around to produce a hollow 85 vertical rectangular tube or magazine of such dimensions as to freely receive match boxes of the ordinary dimensions. This body or magazine of the receptacle is closed at its lower end by the plate 5, and at its 90 upper end has a device for receiving the individual matches and for locking the boxes against removal.

A practical form of this device is illustrated in the drawing and which has a U- 95 shaped metallic frame or tray 6, loosely fitting in the upper end of the tubular body 4, and which has depending strips 7, extending downward through the body to the base plate 5 thereof (see particularly Figs. 1 and 100 2). These strips may have further upward extensions 8, if desired, which project through an out-turned rim 9, on the body 4. The disposition and arrangement of the tray 6, and the strips 7 is such that the tray and 105 strips may be drawn upward through the body 4 until the lower bent-over ends 10 of the strips 7 are drawn up against the ledge or rim 9. There are, however, means for preventing this movement when matches 110 are in the frame or tray 6.

Above the frame or tray 6, there is a cover

plate 11, which, however, does not extend entirely across the top of the receptacle. A narrow space or slot 12 is left adjacent the edge of the tray 6, as clearly shown in Figs. 5 1 and 3. There is also a cut-away portion 13, in the cover 11, large enough for the insertion of a person's finger to withdraw a match from the tray. The form of the tray 6 is made curved or rounded toward the slot 10 12, so that a match may be easily drawn out through such slot with one finger. The width of the slot is, however, not sufficient to draw more than one or two matches from the tray at a time. The cover plate 11 is not 15 fixed in place, but is made hinged to the tray 6, at the point 14. The location of this hinge is, however, somewhat below the upper edge 15, of the corresponding side of the main body 4, so that a shoulder 16, is produced on 20 the hinged plate 11 which prevents the plate being opened upward unless it, together with the tray, are first drawn out of the magazine or body 4. As will presently appear, the tray and its cover are locked against such 25 upward movement as long as there are any matches in the tray. While we have shown this practical construction of the tray and its locking cover, we do not, of course, desire to be limited or restricted thereto, since they 30 may be made of widely varying construction and still secure the essential function, that is to say, of locking the cover of the tray except when the latter is allowed to be drawn upward from the body of the receptacle 4. 35 The practical means which we have shown for locking the tray against upward withdrawal as long as it contains any matches, preferably includes prongs or lugs 17, integral with, or fixed to project from, one side 40 of the main body 4. These prongs 17 overlie the bottom of the tray 6, but the tray is cut away beneath the prongs so that it may be drawn upward past the same, unless there is an intervening object. The cut-away portions 45 of the tray for this purpose are shown at 18, and it will be noted that the cut away parts are large enough to pass the projections. If, however, there are matches contained in the tray 6, one or more of these matches is 50 certain to fall in a transverse position beneath the prongs 17, and in this relation such match acts in conjunction with the prongs as a locking bar or bolt and prevents upward movement of the tray. 55 The lower end of the tubular body or magazine 4 has lateral openings 19 and 20, of which 19 is not sufficiently high to permit the withdrawal of a box therethrough. This opening merely provides a space through 60 which the prepared side of the box is exposed to scratch matches on. The opening 20 is large enough to permit the withdrawal of the box from the magazine. A prepared face of the box is also presented through the 65 opening 20 on which to scratch matches.

Under normal conditions it is impossible to withdraw a box of matches through the opening 20, because the passage is barred by the depending strips 7 with their extensions 8. It is only when the tray 6 is drawn upward together with its depending strips 7 that the opening 20 is available for withdrawing a box from the magazine.

The operation is as follows: The match safe or receptacle being initially empty, is 75 first filled with boxes by pulling upward the tray 6, and inserting the boxes, one by one, through the opening 20, until the magazine is filled. Matches are then poured into the tray 6 until it is well supplied. The tray is 80 then pushed down into the body of the magazine, and in this movement the cover plate 11 is pushed over the tray and the strips 7 are simultaneously thrust across the opening 20. When the tray has been fully pushed down, 85 so that the prongs 17 are moved past the openings 18 of the tray, matches from the tray fall beneath said prongs 17, and thereafter everything is locked in position. Matches cannot be obtained from the tray 90 except individually one by one, because the cover plate 11 only leaves a narrow slot 12 for their withdrawal. At the same time it is impossible to obtain a full box from the lower end of the magazine, because the only 95 opening 20, which is large enough, is barred by the depending strips 7. This relation continues until the matches have been nearly exhausted from the tray 6. The last matches available from the tray 6 are the ones beneath the prongs 17, and when these matches are finally taken out, the device is, of course, 100 unlocked, so that a new box may be obtained from the magazine and its contents poured into the tray.

What we claim, is:—

1. A match safe or receptacle having a magazine to receive match boxes and having a supply of loose matches, and means for locking the boxes in the magazine until the 110 supply of loose matches is used up.

2. A match safe or receptacle having a magazine to receive match boxes and having a supply of loose matches, means for preventing the loose matches being obtained except individually one by one, and means for locking the magazine against the withdrawal of any box until the supply of loose matches is exhausted.

3. A match safe or receptacle having a 120 magazine, a supply of loose matches, means for preventing the use of the loose matches except individually one by one, and means locked by the last match available of said supply for preventing the withdrawal of any 125 box from the magazine.

4. A match safe or receptacle having a magazine adapted to receive a supply of loose matches, and means operated by one of said loose matches for locking the boxes in 130

said magazine against withdrawal therefrom.

5. A match safe or receptacle comprising a magazine and adapted to receive a supply of loose matches, a cover plate for preventing 5 said loose matches being withdrawn except individually one by one, and means made effective by the last match available for locking said cover in position.

6. A match safe or receptacle having a 10 magazine or body adapted to receive boxes, a tray in said magazine or body having depending strips, said magazine having an opening normally barred by said strips through which the boxes may be withdrawn, 15 and prongs overlying said tray and coöperating with the matches therein to prevent its upward movement until the matches are exhausted.

7. A match safe or receptacle having a 20 magazine or body adapted to receive boxes, a

tray in said magazine or body having depending strips, said magazine having an opening normally barred by said strips through which the boxes may be withdrawn, prongs overlying said tray and coöperating with the 25 matches therein to prevent its upward movement until the matches are exhausted, and a cover plate normally locked in position over said tray but released by the upward movement thereof.
